UNITED STATES PATENT OFFICE.

EDWARD FRANCIS WILLOUGHBY AND EDWARD MALET BARFORD REVILL, OF
WELLINGTON, NEW ZEALAND.

STAY FOR CASEMENT AND LIKE WINDOWS.

1,405,082.

Specification of Letters Patent. Patented Jan. 31, 1922.

Application filed July 21, 1919. Serial No. 312,354.

To all whom it may concern:

Be it known that we, EDWARD FRANCIS WILLOUGHBY and EDWARD MALET BARFORD REVILL, subjects of the King of Great Britain, residing at Wellington, in the Dominion of New Zealand, have invented a new and useful Improved Stay for Casement and like Windows; and we do hereby declare the following to be a full, clear, and exact description of the same.

This invention has been designed in order to provide an improved construction of stay for casement and other like forms of windows in which the sashes are hinged within their frames, generally to swing horizontally. The special construction of stay designed provides for the casement sash opening and closing freely and for it being retained at any point within the limits of its movement. Its construction is such also as to provide for the stay bar adjusting itself readily to the variations in the angles necessary to compensate for the different extents to which the sash is opened. In addition the construction provides a lock for locking the sash when it is in the closed position.

The stay is composed generally of two main members, a runner bar that is fastened to the window frame in a line parallel with the plane thereof, and a stay bar that is pivoted at one of its ends by a universal joint to the sash and at the other is pivoted to a sleeve mounted to slide along the runner bar and adapted to be locked thereto at any point.

The invention is illustrated in the accompanying drawings, in which:—

Figure 1 is a side elevation, and

Figure 2 is a front elevation of the stay in position on a window.

Figure 3 is a sectional plan on the line 3—3 of Figure 1.

Figure 4 is a detail view of the means for attaching the stay bar to the sash.

A represents one edge of the window frame and B the edge of the sash frame that closes on to the edge A of the window frame in the closing of the sash by turning on its hinges in the well known manner, the stay being for the purpose of holding such sash open at any point in its opening movement for which the stay provides. The construction of the stay is suitable for a window that swings either in a horizontal or vertical plane, although in the drawings it is shown

as applied to one opening in a horizontal plane.

C is the runner bar. This is attached to the inside face of the frame member A, by means of the brackets C' at each end, so that the bar is carried at a distance from the face of A and extends in a line parallel with the member of the sash B to which the stay is to be connected. Mounted on the said runner bar is a sleeve D that is made to slide freely along the bar and is provided with a thumb screw D' passing through it and engaging the bar, by means of which it may be locked from movement at any point along the bar.

E is the stay bar. This has one of its ends pivotally attached to the sleeve D, as at F and its other end attached to the sash B at a point such that when the sleeve is at the bottom of the runner bar and the sash is in the closed position, the stay bar will extend approximately parallel with the runner bar, as shown in the drawings. The manner of attaching the stay bar to the sash is such as to permit of it assuming any angle relative thereto both in a vertical and horizontal plane. This is effected by attaching a bearing bracket G to the face of the sash B journaling a pin H vertically therein so that its ends project below and above the bracket. The lower end of this pin is forked (as at h Figure 4) and the top end of the stay bar is pivotally secured to such fork.

Consequently the opening of the sash will cause the stay bar to turn out on its pivots F and h the sleeve D sliding up the runner bar B as the angle of the stay bar varies in the vertical plane, and the sleeve rotating on the runner bar and the bearing pin H rotating in its bracket G to accommodate for the varying angles to the horizontal assumed by the stay bar, as the sash opens. Then, by screwing up the thumb screw D', the sleeve may be locked on the runner bar and thus hold the sash in the open position. This arrangement and construction of the parts provide for the sash opening and closing freely, as the stay bar readily adjusts itself to the varying angles and the sleeve runs freely on the runner bar to permit of such variations.

Combined with the stay are means for locking the sash in the closed position. These means consist in a catch lever J that is pivoted on the upper end of the pin H so as to

turn horizontally, and has its outer end so shaped as to be adapted to engage and fit round the runner bar B. This catch lever is made of such a length that when the sash is closed, the catch end may be turned across and sprung over the bar B and will be retained there by the outward strain on the sash. The catch is made with a thumb piece *j* for grasping and turning it, as shown more particularly in Figure 3.

10 We claim:—
A stay for casement and like windows comprising a runner bar having means to fix the same to a window frame, a sleeve slidable 15 on said runner bar, a bracket for attachment

to the sash, a stay bar pivotally connected at one end to the sleeve, a pin mounted for turning movement in said bracket, and a pivotal connection between said stay bar and said pin, and a catch to engage the runner bar, said catch being also pivotally mounted on said pin. 20

In testimony whereof we have signed this specification in the presence of two subscribing witnesses.

EDWARD FRANCIS WILLOUGHBY.
EDWARD MALET BARFORD REVILL.
